UNITED STATES PATENT OFFICE.

CHARLES N. FORREST, OF RAHWAY, NEW JERSEY, ASSIGNOR TO THE BARBER ASPHALT COMPANY, OF PHILADELPHIA, PENNSYLVANIA, A CORPORATION OF WEST VIRGINIA.

BUILDING CONSTRUCTION AND THE LIKE.

Application filed September 23, 1925. Serial No. 58,018.

My invention relates to building construction and the like, and is especially well adapted and advantageous for interior surfaces, as of walls, partitions, ceilings, and the like. Such walls are generally carried by spaced supports (e. g., studding, furring, joists), and surfaced with plaster. I aim to improve, expedite, and cheapen the construction of such walls.

10 In the drawings, Fig. I is a fragmentary perspective view of a wall embodying my invention, partly in section and with various exterior layers partly broken away, illustrating various stages in the construction of 15 such a wall.

Fig. II is a similar view illustrating a somewhat different form of construction.

The construction here shown comprises the usual 2 inch by 4 inch or other studding 20 placed at 16 inch or other suitable intervals (on centers). On this studding 5 is a covering or layer 6 of foraminous character, such as a wire mesh like chicken wire secured to the supports 5 by nails or staples 25 7, and preferably stretched taut enough across the intervals between the supports to be reasonably firm and unyielding. Over this backing 6 is secured a covering or layer 30 8 of flexible bituminous "stucco base", as it is termed, a material resembling mineral-surfaced bituminous roofing, and formed by saturating and coating bibulous paper or rag 35 felt with hot, molten bitumen and embedding coarse mineral granules in the bitumen while it is still soft. This gritted base layer 8 may be secured in any suitable manner, as by 40 nails 9 driven through the metallic mesh backing 6 into the supports 5. It may preferably be in vertical strips overlapping vertically on the studding 5, with horizontal lapped or other end joints 10. Plaster or 45 stucco 11 may be applied wet directly to this base 8, with a trowel or a float. During this operation, the backing 6 sustains the 50 flexible base 8 against flexing.

Such a backing 6 is particularly advantageous in supporting the horizontal laps 10 of the flexible bituminous base, since it is at these laps 10 that sagging is most likely to occur. In some cases, indeed, it may even suffice to employ the backing 6 in the form of

strips 6' some six inches wide, stretched from stud to stud directly under each horizontal lap 10 only, as shown in Fig. II, without any backing whatever under the rest 55 of the bituminous base.

While any convenient or preferred size of wire mesh may be used for the backing 6, a very thin gauge of wire and a mesh of one inch (or more) will generally be found 60 satisfactory. The wire need not necessarily be galvanized or otherwise protected against rusting, but may be of ordinary black iron, since its decay during the subsequent life of the structure will have no bearing on its 65 important function of supporting the bituminous base during the application of the plaster.

The practical advantage of my backed 70 bituminous stucco base construction over ordinary metallic lathing will be readily apparent. With expanded metal lathing, the plaster must penetrate its meshes in substantial amounts in order to key to it properly; but the mineral surfaced flexible stucco base is impermeable to the plaster, and holds the latter without necessity for penetration. At the same time, the metallic mesh backing imparts to the wall as good 75 practical rigidity during plastering as in the old construction.

Having thus described my invention, I claim:—

1. A wall construction comprising, in combination with spaced supports and substantially impermeable mineral-surfaced flexible bituminous stucco base thereon, a foraminous backing for said base extending between said supports.

2. A wall construction comprising, in combination with spaced supports and substantially impermeable mineral-surfaced flexible bituminous stucco base thereon, a metallic mesh backing for said base extending between said supports.

3. A wall construction comprising, in combination with spaced supports and substantially impermeable mineral-surfaced flexible bituminous stucco base thereon, a wire mesh backing for said base stretched 90 taut across the intervals between said supports.

4. A wall construction comprising, in combination with studding and substantially impermeable mineral-surfaced flexible bituminous stucco base thereon, a backing of chicken wire for said base stretched over said supports.

5. A wall construction comprising spaced supports, a metallic mesh backing secured to

and extending between said supports, and substantially impervious mineral-surfaced ¹⁰ bituminous stucco base over said backing, independently secured to said supports.

In testimony whereof, I have hereunto signed my name at Maurer, N. J., this 17th day Sept., 1925.

CHARLES N. FORREST.
